Res 689

N. S. Vedder, of Troy, N.Y.

Assignor to

G. F. Gilley, of St. Louis, Mo.

Letters Patent No. 689, Dated Jan'y. 23. 1855.

The schedule referred to in these Letters Patent, and making part of the same

To all whom it may concern.

Be it known that I, N. S. Vedder, of Troy in the county of Rensselaer, and State of New York, have invented or produced a certain new and useful design of

Dec 689

34
in front Parlor Stove, which I call the "Island Queen" and I do hereby declare that the following is a full, clear, and exact description of the same, reference being had to the accompanying perspective drawing and letters of reference marked thereon, making part of this specification.

My design of parlor Stove consists of the top plate (A) with the ornamental border moulding (a), the ornamental moulding (b) around the pipe collar, and the basket work surface (C), (B) is the front plate, designed as follows. (d, d.) are fluted half columns with caps and bases, and arranged on each side of the fire chamber, (e) is the key of the ornamental arch (f, f) over the fire chamber, (g, g.) are scroll ornaments on each side at the top, (h, h.) are scalloped ornaments on each side at the bottom, (i, i.) are ornamental borders, C is the bottom plate, with the ornamental border moulding (j, j), D is the blower decorated with the ray work of coves and beads, (k, k), E is the cross front plate, ornamented with the arches, and such panels (l, m.), F is the damper plate ornamented with arches (n), G is the hearth plate with moulding (o).

Having described my design of Parlor Stove plates, what I claim as new and desire to secure by Letters Patent is, The ornamental design and configuration of parlor stove plates, such as herein described, and represented in the annexed drawing.
